(Cl. D13—1)

To all whom it may concern:

Be it known that I, Jean A. Hardesty, a citizen of the United States and resident of the city of Altadena, county of Los Angeles, State of California, have invented a new, original, and ornamental Design for an Automobile Service Station Island, of which the following is a specification, reference being had to the accompanying drawings, forming a part thereof, in which:

Fig. 1 is a perspective view of the automobile service station island, showing my new design;

Fig. 2 is a side elevation;

Fig. 3 is a rear end elevation;

Fig. 4 is a front end elevation; and

Fig. 5 is a reduced top plan view thereof.

I claim:

The ornamental design for an automobile serv-
ice station island, substantially as shown.

JEAN A. HARDESTY.
